UNITED STATES PATENT OFFICE.

CHARLES F. TAYLOR, OF HARTFORD, AND FREDERICK J. LAROCK, OF EAST HARTFORD, CONNECTICUT.

RECORDING MECHANISM.

SPECIFICATION forming part of Letters Patent No. 792,680, dated June 20, 1905.

Application filed February 2, 1905. Serial No. 243,809.

To all whom it may concern:

Be it known that we, CHARLES F. TAYLOR, a resident of Hartford, and FREDERICK J. LAROCK, a resident of East Hartford, in the county of Hartford and State of Connecticut, citizens of the United States, have invented certain new and useful Improvements in Recording Mechanism, of which the following is a full, clear, and exact specification.

This invention relates to recording mechanism, and more especially to that class thereof whereby the speeds attained, distances covered, and time consumed by vehicles in making certain trips may be permanently recorded; and it has for one of its objects the provision of an instrument of this class in which a stylus or other marker will make an impression on the record-sheet after each completion of a predetermined distance run.

The invention has furthermore for its object the provision of mechanism in which the relative positions of the record-sheet and stylus are continuously and constantly changed by the advancement of one of said members through a chronometrical device—as, for instance, a time-clock.

A further object of the invention resides in the provision of an electromagnet for causing the stylus and record-sheet to contact and the combination therewith of a device for energizing the same and controlled by one of the vehicle-wheels.

Further objects of the invention will be apparent in the construction and organization of the several elements, as will be hereinafter described, and particularly pointed out in the claims.

In the accompanying drawings, in which similar characters denote similar parts, Figure 1 is a face view of a recording instrument embodying our invention. Fig. 2 represents a horizontal section taken below the dial-plate and substantially on a line 2 2 indicated in Fig. 3. Fig. 3 shows a vertical section on line 3 3 of Fig. 1. Fig. 4 is a side view of the mechanism for controlling the action of the stylus, and Fig. 5 is a face view thereof and includes a diagram of the elec-

trical conductors between the controlling mechanism and the recording instrument.

Briefly stated, the mechanism shown in the drawings comprises a stylus which is carried on the uniformly - advancing minute-hand of an ordinary time - clock. As this hand is advanced by the clock-movement its outer end travels within the zone of an electromagnet, which when energized will pull the hand against the dial-plate, and thus cause the stylus to puncture the record-disk stationary on said plate. The energization of the magnet is accomplished through closing a normally open circuit by a switch mechanism operated by the vehicle-wheel in such a manner that when the vehicle completes a run of one-eighth of a mile the circuit will be momentarily closed. Consequently eight punctures will be made for each mile traveled and the speed ratio of the vehicle can be readily ascertained by considering the time which has elapsed between two succeeding punctures. For instance, if a minute elapses from the time one puncture is made until the second puncture takes place the speed of the vehicle would be (for an hour) equal to sixty-eighths of a mile, or, in other words, seven and one-half miles per hour, but if two punctures should occur during a minute the rate would be fifteen miles per hour running speed. With these facts as a basis the operator is enabled to "see" the speed at which the vehicle is traveling by comparing the frequency of the punctures with the minute-lines of the record-sheet. Inasmuch as it is desirable to provide a record-sheet which is of sufficient capacity to cover at least one full day's run, the stylus is gradually moved along on the hand toward the center of the clock, so that when the minute-hand has completed an hour's movement the stylus will begin on another hour-line, thus keeping the punctures on each hour-circle distinct by themselves, the hour-lines commencing with six a. m. and gradually diminishing in diameter until the twenty-four hours of the day have been provided for.

In the drawings, 10 denotes a casing having near the bottom thereof a flange 11, on which

a base-board 12 is firmly secured. Mounted on this base-board is a time-clock mechanism T, which may be of any desired construction and which comprises a staff 13 for actuating the minute-hand 14. Loosely mounted on the staff 13 is a sleeve 15, adapted to receive the quill of the hour-hand 16 and operated at a ratio of one to twelve by the usual gear-train (indicated in a general way by 17) and disposed below a dial-plate 18, which is supported on the casing 10, as shown in Fig. 3, and has a comparatively small permanent dial 19 for use in connection with the hour-hand 16. The dial-plate 18 is preferably made of wood and supports on its upper face a stationary but removable record sheet or disk R', having a central aperture corresponding to the outside diameter of an annular flange 18', whereby it is properly located on the dial-plate 18.

The minute-hand 14 consists in the present instance of a resilient bar supported on the staff 13 and advancing therewith, and it has at its outer end a soft-iron armature 14', traveling over an annular field-plate 20, which is secured to the top of the casing 10 and serves to inclose a coil of wire 21 within an annular groove or recess 22, provided therefor. The ends of the wire coil 21 are secured to terminals 23 24, respectively, and when a current of electricity is sent through the coil the field-plate 20 will become magnetized and attract the armature 14', thus causing an indicator or stylus S, carried on the minute-hand 14, to puncture the record-sheet R'. It may be stated at this time that it is of course immaterial what the nature of the stylus S may be, it being evident that any suitable marking device, either with or without ink, may be employed in lieu of the puncturing-point herein illustrated and described without in any way affecting the invention.

Means are provided for varying the resiliency of the bar 14 and for locating the armature 14' within the magnetic zone of the field-plate 20, these means consisting substantially of a stiff arm 25, secured on the minute-staff 13 and perforated at its free end to receive a screw 26, attached to said bar 14 and having a nut 27 for regulating the position of the minute-hand relatively to the arm 25.

As above stated, the record-sheet is of sufficient capacity to cover twenty-four hours, and by referring to Fig. 1 it will be seen that the record-sheet has radial lines dividing the same into sixty minute-spaces and also a spiral line s, the outer end of which begins at the index-line i, disposed opposite the numeral "XII" of the permanent dial 19. The spiral line s indicates the path of the stylus S in its revolution around staff 13, each convolution approaching the center a predetermined distance, so that the succeeding hours may be readily distinguished. The first convolution covers the period from six a.m. to seven a.m.,

the second from seven a.m. to eight a.m., and so on until the last convolution ends again at six a.m., thus giving to the record-sheet a capacity of twenty-four hours, each subdivided into minutes.

Any suitable mechanism may be employed for moving the stylus progressively inward, and in the preferred form thereof shown the bar 13 constitutes a guide for a slide 30, adapted to be moved longitudinally thereon by a screw 31, journaled in bearings 32 and in screw-threaded engagement with a two-part nut 33, the sections of which are formed at the end of a pair of levers 34, pivoted at 35 on the slide 30 and normally closed by springs 36, while they have finger extensions 37, whereby the nut-sections may be disengaged from and slide along the screw for positioning and resetting the slide thereon. The inner end of the screw 31 carries a pinion 40 in engagement with a gear 41, which may be stationary, but is preferably mounted, for the sake of convenience, on the sleeve of the slowly-moving hour-hand, the organization being such as to cause the stylus-slide to move inward about one-tenth of an inch during each revolution of the minute-hand. When the slide 30 has reached the limit of its inward movement, the nut-sections 33 will be automatically disengaged from the screw 31 by engaging a conical portion 45 of the screw 31.

The entire mechanism thus far described is mounted on and forms a part of the casing 10, which is provided with a cover-ring 50, having a glass 51, which permits a plain view of the dial and record-sheet and incloses the mechanism against injury.

The device whereby the magnet-coil 21 is periodically energized at each completion of a one-eighth-mile travel of the vehicle is clearly shown in Figs. 4 and 5, in which W denotes the vehicle-wheel journaled on the vehicle-axle A and carrying a tappet or striker 60 of ordinary construction. The switch mechanism is mounted on a bracket 61, secured to the axle A, and comprises a star-wheel 62, secured upon a spindle 63, which is journaled in the bracket 61 and carries a pinion 62' in engagement with a gear 63', mounted upon a spindle 64, also journaled in the bracket 61 and having a pinion 65 secured thereto. The pinion 65 meshes in a gear 66, which is loosely mounted for rotation on the spindle 63 and carries an insulated disk 67, provided with a metallic strip 68, which constitutes a circuit-maker and serves as a medium whereby an electric connection is established once during each complete rotation of the disk 67 and its gear 66 between a pair of brush-contacts 70 71, which are normally insulated from each other on an insulating-block 72, held on the bracket 61. The gear 66 and disk 67 are prevented from longitudinal displacement on the spindle 63

by means of a collar 73, and the ratio of gearing is in the present instance such that seventy-two rotations of the thirty-six-inch vehicle-wheel W, equaling a travel distance of one-eighth mile, will result in one full rotation of the disk 67, therefore connecting the brushes 70 71 at the completion of each eighth mile and closing the magnet-circuit, which comprises brush 70, battery B, terminal 23, coil 21, terminal 24, conductor 24', brush 71, and strip 68.

The actual work performed by our improved recorder and the significance of the markings on the record-sheet can be readily ascertained by referring to Fig. 1, which shows a record of a trip, as follows: The vehicle started from H at 7.20 a. m. The next nine-minute run to I shows twelve marks, which means three-fourths of a minute used 15 for each mark of one-eighth of a mile and a total distance of one and one-half miles traversed between 7.20 and 7.29 a. m. Now if it took three-fourths of a minute to run one-eighth of a mile, as the record-sheet plainly 20 shows, it would take at the same speed six minutes to run one mile, so that we find that the vehicle ran at a speed of ten miles per hour between 7.20 and 7.29 a. m. and traversed a distance of one and one-half miles. 25 Between 7.29 and 7.35 a. m., a period of six minutes between I and K, we find sixteen marks, equaling a distance of two miles and showing a speed of one-eighth of a mile for each three-eighths of a minute, or a twenty- 30 mile rate. Between K and L the time consumed was thirty minutes, (from 7.35 to 8.05.) Twelve marks mean a distance of one and one-half miles traversed, two and one-half minutes for each one-eighth of a mile or a 35 speed rate of three miles per hour. From L to M it took from 8.05 to 8.08 a. m., three minutes, to accomplish four one-eighths miles at three-fourths of a minute each, showing a speed-rate of ten miles per hour. 40 In a similar manner the distance of one-fourth of a mile from M to N was covered between 8.08 and 8.09 $\frac{1}{4}$ a. m., equal to one and one-fourth minutes at a speed rate of twelve miles per hour. From N to O the distance is 45 one-half mile, covered in one and one-half minutes at the rate of twenty miles. From O to P it took seven minutes to travel three and one-half miles at a speed of thirty miles per hour. From P to Q is a distance of one 50 and one-half miles, covered in six minutes at a fifteen-mile rate. From Q to R nine minutes were consumed in traversing three miles at a twenty-mile rate. From R to T is a distance of two miles, covered at a ten- 55 mile rate in twelve minutes, and from T to U it took twenty-nine and three-fourths minutes to travel one and one-half miles at a speed rate of three miles per hour, the total distance from the starting-point H being 60 seventeen and three-fourths miles, and the 65

time consumed was from 7.20 to 9.14 $\frac{1}{2}$, a period of one hour and fifty-four and one-half minutes.

From the foregoing it is evident that our improved recording device preserves an accurate account of the performance of a vehicle during any one day, regarding the distances traveled between given points, the speed attained, and also the time of the day when the occurrences took place. 75

Having thus described our invention, what we claim is—

1. The combination, with an electric circuit comprising an electromagnet, a record-sheet, a marking device coöperative therewith and having an armature, and a time mechanism for advancing said marking device at a uniform rate of speed; of a rotatable wheel; and means for closing said circuit and for actuating said marking device upon the completion of a predetermined movement of said wheel. 80

2. The combination, with a record-sheet, a marking device comprising an armature and a time mechanism for advancing said marking device at a uniform rate of speed; of a wheel; an electromagnet coöperative with said armature; and means for energizing said magnet upon the completion of a predetermined movement of said wheel. 95

3. The combination, with a record-sheet, a marking device, an armature carried thereby; and a time mechanism for advancing said marking device at a uniform rate of speed; of a wheel, an electromagnet for causing engagement between the record-sheet and the marking device; and means for energizing said magnet upon the completion of a predetermined movement of said wheel. 100

4. The combination, with a record-sheet, and a marking device, of means for advancing one of said members relatively to the other and comprising an arm, a slide for supporting said marking device and movable on said arm, and means carried on the arm and for shifting said slide on the arm. 105

5. The combination, with a record-sheet, and a marking device, of a time mechanism for advancing one of said members relatively to the other, and comprising a uniformly-advancing hand; a slide for supporting said marking device and movable on said hand; a two-part nut carried by said slide; and a screw on the hand for shifting said slide gradually during the revolution of said hand. 115

6. The combination, with a record-sheet, of a marking device, a time mechanism for advancing one of said members relatively to the other and comprising a uniformly-advancing hand; a slide for supporting said marking device and movable on said hand; a screw for gradually shifting said slide; and means for disconnecting said slide from the screw. 125

7. The combination, with a record-sheet 130

and a marking device; of a time mechanism for advancing one of said members relatively to the other and comprising a uniformly-advancing hand; a slide for supporting said marking device and movable on said hand; a two-part nut carried by said slide; a screw for shifting said slide gradually during the revolution of said hand and having a conical portion for disconnecting said slide from the screw at the end of the shifting movement.

8. The combination, with a record-sheet; of a marking device, a time mechanism for advancing one of said members relatively to the other and comprising a uniformly-advancing hand, a slide for supporting said marking device and movable longitudinally on said hand; a screw for shifting said slide

on the hand; and means for positioning the slide on the screw.

9. The combination, with a record-sheet; of a marking device, a time mechanism for moving one of said members relatively to the other and comprising a hand; a slide for supporting said marking device and movable on said hand; a screw in engagement with said slide; a pinion on said screw; and a gear in engagement therewith and for rotating said screw to shift said slide longitudinally of the hand.
